UNITED STATES PATENT OFFICE

114,588

DESIGN FOR A COMBINED CARRIAGE AND
SPACER GUIDE FOR MEAT SLICING MA-
CHINES

Thomas L. Hand, Cincinnati, Ohio, assignor to
The Cincinnati Time Recorder Company, Cin-
cinnati, Ohio, a corporation of Ohio

Application May 16, 1938, Serial No. 77,203

Term of patent 7 years

To all whom it may concern:

Be it known that I, Thomas L. Hand, a citizen of the United States and a resident of Cincinnati, in the county of Hamilton and State of Ohio, have invented a new, original, and ornamental Design for a Combined Carriage and Spacer Guide for Meat Slicing Machines, of which the following is a specification, reference being had to the accompanying drawing, forming part thereof.

In the drawing:

Figure 1 is a perspective view of a combined carriage and spacer guide for meat slicing machines taken from one side thereof embodying my new design and showing the meat clamp arm in elevated position; and

Figure 2 is a perspective view thereof taken from the opposite side of that shown in Figure 1 with the meat clamp in lowered position.

The novel features of the design reside in the proportions and contours of the parts forming the meat receiving carriage and the supporting members for the meat clamp, substantially as shown in the drawing.

I claim:

The ornamental design for a combined carriage and spacer guide for meat slicing machines, substantially as shown and described.

THOMAS L. HAND.
